STAPLING PLIERS

Stephen A. Crosby, New York, N. Y., assignor to
Speed Products Company, Long Island City,
N. Y.

Application April 26, 1938, Serial No. 204,288

15 Claims. (Cl. 1—49)

The invention relates to a stapling machine of the type particularly adapted to be utilized as plier or tacker and an object thereof is realized in the provision of an improved and serviceable plier wherein a staple carrying arm is interposed and pivotally sustained between a pair of swingably associated upper and lower complements or handles, the upper of which is operatively connected to a slidable plunger for driving a staple from a vertical staple driveway of the magazine of the arm while the lower complement or base of the pair swingably carries a spring controlled cradle having means for automatically but disengageably interlocking with the staple carrying magazine of the arm in which event if the lower complement is swung relatively towards the magazine, staple indentations of an anvil fixedly sustained by the base is caused to be in vertical alinement with the vertical staple driveway of the magazine to receive and deform the staple on leaving the staple raceway. Other objects, advantages, and features of the invention will be more readily understood from the teachings of the following detailed description considered in the light of the accompanying drawings in which:

Fig. 1 is a perspective view of the hand staple plier according to my invention.

Fig. 2 is a view similar to Fig. 1 but illustrating the staple carrying arm uncoupled from the anvil carrying and swingable base.

Fig. 3 is a vertical and longitudinal sectional view of Fig. 1 shown partly broken away.

Fig. 4 is an exploded view of the driving connection between the upper handle and staple driving plunger.

Fig. 5 is a sectional view on the line 5—5 of Fig. 3.

Fig. 6 is an exploded view showing the leaf spring, the rockable cradle, and the fulcrum pin against which the cradle is pivotally and yieldingly held by the leaf spring.

Fig. 7 is an enlarged sectional view on the line 7—7 of Fig. 3.

Fig. 8 is a sectional view on the line 8—8 of Fig. 3.

Fig. 9 is a plan view of the latch for disconnectably locking the cover and magazine of the split arm.

Fig. 10 is a sectional view on the line 10—10 of Fig. 7.

Fig. 11 is an open perspective view of the plier.

Fig. 12 is a sectional view on the line 12—12 of Fig. 3, and

Fig. 13 is a sectional view on the line 13—13 of Fig. 3.

The plier according to the invention includes a frame F constituting a pair of handles comprising an upper component or actuator 10 and a lower component or base 11. Depending flared ears 12 of component 10 and the upstanding flared ears 13 of component 11 are pivotally mounted on the upset fulcrum pin 14 which also 10 pivotally sustains spaced ears 15 depending from the rear part of cover 16 of the staple carrying arm generally denoted 17, and the spaced ears 18 extending upwardly at the rear of the magazine 19 of the arm. Thus by the present arrangement the complements of the frame F may be 15 swung towards or away from the arm 17. It will be noted that the ends of inwardly curved spring clip 14' resiliently retained on pin 14 cooperates with the enlarged portions 14'' of the latter and 20 the inner faces of the depending ears 15 to prevent longitudinal displacement of this fulcrum pin.

Approximately mounted within magazine 19 is a rail 20 defining with the front wall 21 of the arm 17 a vertical staple receiving driveway 22 adapted to receive the foremost staple 23 of the staple strip 24 slidably guided on rail 20. For urging the foremost staple of the strip into vertical alinement with the driveway 22, a spring 25 controlled channel shaped follower 25 is provided and a struck out eye 26 of the follower is threaded onto an end coil 27 of helicoidal spring 28 which has an intermediate portion trained over a rotatable roller 29 mounted on a shaft 30 slidably 35 guided in the spaced gaps 31 in sides 38 of the rear channel shaped member 39 forming the rear part of the cover 16.

The upper end 34 of the helicoidal spring 24 has one or more coils 35 hooked on offset projection 36 of a block 37 fixedly secured to one side 38 of the channel shaped member 39.

Slidably guided in the spaced slots 31' of the sides 32 of front channel shaped member 33 and the horizontally alined slots 31 in the front part 45 of cover 39 is a latch 40 having laterally extending conveniently accessible wings 41. With the cover closed in respect to the magazine as shown in Fig. 1, intermediate parts 42 (Fig. 9) of the latch are received in alined gaps 42' of the upstanding wings 43 extending upwardly from the sides of the magazine 19, that is, in the closed relation of the magazine and cover helicoidal spring 28 normally urges slidable latch 40 rearwardly to interlock with the wings 43, however 50 55 concomitantly urging the slidable follower 25 for-

wardly to urge the staple strip forwardly and dispose the foremost staple in alignment with the vertical raceway 22.

Slidably guided by the cover 16 is a channel shaped plunger 44 (Fig. 4) which carries a staple ejecting blade 45. This plunger is normally held elevated by end 46 of leaf spring 47 abutting lugs 48 of the sides 49 of the channel shaped plunger 44. This leaf spring 47 has its other end 50 suitably fixed to a mount 51 fixed within the cover 16.

Fixedly secured to the front offset manipulator head 52 of the swingable actuator or handle 16 is a channel shaped bracket or coupling 53 having sides 54 each provided with a recess 55 for receiving and interlocking with inwardly turned lugs 56 projecting from sides 49 of the plunger. If therefore a downwardly directed blow is imparted to the manipulating head 52, bracket 53 causes lugs 56 to be shifted downwardly and consequently the plunger is driven in a corresponding direction.

If the plunger is moving downwardly, the blade 45 meets the foremost staple and drives the latter through the raceway and the legs of the driven staple penetrate papers or the like interposed between the fixed anvil 57 and the magazine. Ultimately the lugs of the ejected staple meet the clinching indentations 58 and the staple becomes appropriately deformed for fastening purposes.

According to the invention, a cradle 60 (Fig. 6) is rotatably or pivotally associated with the base or lower handle 11 of the frame F to disconnectably interlock with the magazine. For this purpose, a fixed fulcrum pin 61 is employed. This fulcrum pin is fastened to ears 13 of the base 11. The cradle is in the form of a channel shaped member and comprises a base 62 seated on the free end of the cantilever leaf spring 63 having its forward end 64 anchored by rivets 65 to the swingable base 11. Sides 66 of the cradle each include a slot or bearing 67 for receiving reduced portions 68 of fulcrum pin, and when assembled portions of the sides 66 adjacent slots 67 pivotally and loosely interlock with the grooves defining the reduced portions 68 and the leaf spring 63 normally holds stop 69 against the fixed pin 61. Thus the cradle is held in a normally raised position.

The cradle is also provided with an upstanding latch 70 having a forwardly curved or inclined lip 71, and spaced notches 72 defining the reduced portion 73. Extending forwardly of the sides of the cradle are the projections 74 each having a laterally extending lug or finger manipulator 75.

With the magazine disconnected from latch 70 as shown in Fig. 2 the cover may be swung relative to the base in which event the cover may be used as a tacker. If the cover be swung towards the base shoulders 76 defining a portion of the narrow opening 77 in the bottom wall of the magazine 19, simultaneously abut the curved lip 71 of the latch 70, causing the latter to be tilted forwardly and the manipulating fingers 75 downwardly, that is, the cradle is slightly rotated in a clockwise direction until the rectilinear part 78 of the latch starts to abut faces 79 of the spaced shoulders 76 in which case the head 71 of the latch is received in the enlarged or expanded square shaped opening 80 which together with the narrow or restricted opening 77 constitute a T shaped opening or slot. Therefore further movement of the arm of the magazine towards the base causes shoulders 76 of the magazine to ultimately line up with slots 72 of the latch 70

in which case spring 63 releases its energy, the cradle is rotated in a clockwise direction, causing the reduced portion 73 of the latch to be received by the narrow opening 77 of the magazine 19 and the shoulders 76 to be received by slots 72 of the latch 70, and the rear transverse face 79 of the narrow opening 77 constitutes stop means to limit clockwise movement of the cradle as is evident from Figs. 3 and 8.

To disengage the latch of the cradle from the magazine either of the manipulating fingers 75 which are conveniently accessible and extend laterally of the magazine may be depressed, causing the cradle to be rotated in a counterclockwise direction against the energy of leaf spring 63 until the reduced portion 73 of the latch is free of spaced shoulders 76 of the magazine in which case the inclined lip 71 of the latch is within wide or expanded opening 80 and thus becomes free of the magazine, or in other words, the latter is unlocked from the magazine, and may be swung relative to the base.

Where it is desired to open the arm 17 to obtain access to the rail, this can be accomplished by first shifting latch 40 forwardly to disconnect the latter from the magazine, then swinging the cover away from the magazine in which event access may be had to the rail. If the cover be swung rearwardly, the staple follower is automatically retracted. If the cover be swung towards the magazine cam surfaces 81 of wings 43 cause latch 40 to shift forwardly until portions 42 of the latter line up with slots 42' of the wings 43 whereupon the action of the helicoidal spring causes the roller 29 to retract and shift portions 42 into slots 42' of wings 43. In this way the cover and magazine are automatically locked and preparatory to such locking action tongue 82 of the cover fits into notch 83 of the magazine to facilitate proper positioning of the cover in respect to the magazine.

As previously pointed out the swingable complements of frame F are utilized in the matter of effecting the discharge and deforming of a foremost staple. For purposes of specification, these complements may be considered as swingable curved handles which if moved towards each other when the lower complement is locked by the cradle and when the split arm 17 is closed, operate to position the clinching indentations of the anvil under staple driveway while the plunger drives the foremost staple out of the arm to be deformed by the anvil. These handles are also properly shaped to be conveniently grasped by one hand of the operator and after each clinching operation, the handles are automatically moved outwardly to their normal position by the leaf springs 47 and 63.

When the cradle is locked to the magazine, walls 84 and 85 of slots 72 of the latch thereof, straddle shoulders 76 of the magazine. If therefore the magazine is moved downwardly shoulders 76 abut walls 84 thus causing the latch to be shifted downwardly against the energy of spring seat 63. This action takes place on each downward stroke of the driver if the cradle be interlocked with the magazine and although the cradle is idly shifted downwardly advantage is taken of this action in that the spring seat 63 is flexed, and such stored energy is utilized to automatically return the swingable base 11 to its normal position when hand pressure be removed from the handles and during such automatic retraction shoulders 76 abut walls 85 of the spaced slots 72 of the latch 70 of the cradle.

As many changes could be made in the above described construction and many widely different species or structural embodiments could be devised without departing from the scope thereof, it is intended that all matter hereinbefore described in the specification and illustrated in the accompanying drawings shall be interpreted as illustrative and not in a limiting sense.

I claim:

1. In combination, an upper handle comprising a head and a downwardly sloping rear portion, a lower handle comprising an upwardly sloping rear portion received and straddled by said downwardly sloping portion, a staple carrying arm comprising a magazine and a cover interposed between said handles and having a rear part housed by said sloping portions, spring controlled staple driving means slidably guided by said arm, fulcrum means pivotally sustaining said sloping portions and said magazine and cover, movable locking means for disconnectably securing said magazine and cover, coupling means interconnecting said upper handle and driving means, a staple clinching anvil carried by said lower handle, and locking means sustained by said lower handle for disconnectably engaging said arm.
2. In combination, an upper handle comprising a head and downwardly sloping rear portion, a lower handle comprising an upwardly sloping rear portion, a staple carrying arm interposed between said handles and having a rear part housed by said sloping portions, spring controlled staple driving means slidably guided by said arm, fulcrum means pivotally sustaining said sloping portions and said rear part, driven means interconnecting said upper handle and driving means, a staple clinching anvil carried by said lower handle, a rockable cradle sustained on said lower handle and having means for disengageably interlocking with said arm, and a spring seat for said rockable cradle.
3. In combination, an upper handle comprising a head and downwardly sloping rear portion, a lower handle comprising an upwardly sloping rear portion, a staple carrying arm interposed between said handles and having a rear part housed by said sloping portions and including a magazine comprising an expanded and a restricted opening in communication, spring controlled staple driving means slidably guided by said arm, fulcrum means pivotally sustaining said sloping portions and said rear part, coupling means interconnecting said upper handle and driving means, a stapling clinching anvil carried by said lower handle, rockable locking means pivotally sustained on said lower handle and comprising a base having an upstanding latch having means adapted to enter said expanded opening and means for interlocking with said magazine adjacent said restricted opening, and a spring sustained by said lower handle for resiliently supporting said base.
4. In combination, an upper handle comprising a head and downwardly sloping rear portion, a lower handle comprising an upwardly sloping rear portion, a staple carrying arm interposed between said handles and having a rear part housed by said sloping portions and including a magazine having a large opening and a narrow opening in communication, spring controlled staple driving means slidably guided by said arm, fulcrum means pivotally sustaining said sloping portions and the rear part of said arm, coupling means interconnecting said upper handle and
5. In combination, an upper handle comprising a staple clinching anvil carried by said lower handle, cradle locking means sustained on said lower handle and having an upstanding latch provided with a terminal inclined portion for abutting said magazine when entering said large opening and including a reduced portion adapted to be received in said narrow opening, and spring means for urging said reduced portion against a wall of said narrow opening.
- 10 6. In combination, an upper handle comprising an offset head and downwardly sloping rear portion, a lower handle comprising an upwardly sloping rear portion received and straddled by said downwardly sloping portion, a staple carrying arm interposed between said handles and having a rear part housed by said sloping portions, spring controlled staple driving means slidably guided by said arm, fulcrum means pivotally sustaining said sloping portions and the rear part of said arm, coupling means interconnecting said upper handle and driving means, a staple clinching anvil carried by said lower handle, other fulcrum means carried by said lower handle, a cradle having means rotatably guided by said other fulcrum means, a latch carried by said cradle, and a spring for holding said cradle against said other fulcrum means.
- 15 7. In combination, an upper handle comprising a head and downwardly sloping rear and flared portion, a lower handle comprising an upwardly sloping rear and flared portion telescopically associated with said downwardly sloping portion, a staple carrying arm interposed between said handles and having a rear part housed by said sloping portions, spring controlled staple driving means slidably guided by said arm, fulcrum means pivotally sustaining said sloping portions and said rear part, coupling means interconnecting said upper handle and driving means, a staple clinching anvil carried by said lower handle, rockable locking means sustained by said lower handle for disconnectably engaging said arm, and spring means for yieldingly supporting said rockable locking means.
- 20 8. In combination, a magazine having spaced sides, a handle, means pivotally sustaining said magazine and said handle, fulcrum means, and a cradle pivotally sustained against said fulcrum means and having an upstanding latch for interlocking with said magazine and having forwardly projecting means including finger gripping means extending laterally and outwardly of the body of said cradle and laterally and outwardly of said sides and adjacent thereto for actuating said latch to remove the latter from interlocking relation with said magazine.
- 25 9. In combination, a staple carrying magazine having a bottom wall, a handle, means pivotally sustaining said magazine and said handle, a leaf spring carried by said handle, fulcrum means traversing said handle, and a rockable cradle supported by said spring pivotally against said ful-
- 30 10. In combination, a head and downwardly sloping rear and flared portion, a lower handle comprising an upwardly sloping rear and flared portion telescopically associated with said downwardly sloping portion, a staple carrying arm interposed between said handles and having a rear part housed by said sloping portions, spring controlled staple driving means slidably guided by said arm, fulcrum means pivotally sustaining said sloping portions and said rear part, coupling means interconnecting said upper handle and driving means, a staple clinching anvil carried by said lower handle, rockable locking means sustained by said lower handle for disconnectably engaging said arm, and spring means for yieldingly supporting said rockable locking means.
- 35 11. In combination, a magazine having spaced sides, a handle, means pivotally sustaining said magazine and said handle, fulcrum means, and a cradle pivotally sustained against said fulcrum means and having an upstanding latch for interlocking with said magazine and having forwardly projecting means including finger gripping means extending laterally and outwardly of the body of said cradle and laterally and outwardly of said sides and adjacent thereto for actuating said latch to remove the latter from interlocking relation with said magazine.
- 40 12. In combination, a staple carrying magazine having a bottom wall, a handle, means pivotally sustaining said magazine and said handle, a leaf spring carried by said handle, fulcrum means traversing said handle, and a rockable cradle supported by said spring pivotally against said ful-
- 45 13. In combination, a magazine having spaced sides, a handle, means pivotally sustaining said magazine and said handle, fulcrum means, and a cradle pivotally sustained against said fulcrum means and having an upstanding latch for interlocking with said magazine and having forwardly projecting means including finger gripping means extending laterally and outwardly of the body of said cradle and laterally and outwardly of said sides and adjacent thereto for actuating said latch to remove the latter from interlocking relation with said magazine.
- 50 14. In combination, a staple carrying magazine having a bottom wall, a handle, means pivotally sustaining said magazine and said handle, a leaf spring carried by said handle, fulcrum means traversing said handle, and a rockable cradle supported by said spring pivotally against said ful-
- 55 15. In combination, a staple carrying magazine having a bottom wall, a handle, means pivotally sustaining said magazine and said handle, a leaf spring carried by said handle, fulcrum means traversing said handle, and a rockable cradle supported by said spring pivotally against said ful-
- 60 16. In combination, a staple carrying magazine having a bottom wall, a handle, means pivotally sustaining said magazine and said handle, a leaf spring carried by said handle, fulcrum means traversing said handle, and a rockable cradle supported by said spring pivotally against said ful-
- 65 17. In combination, a staple carrying magazine having a bottom wall, a handle, means pivotally sustaining said magazine and said handle, a leaf spring carried by said handle, fulcrum means traversing said handle, and a rockable cradle supported by said spring pivotally against said ful-
- 70 18. In combination, a staple carrying magazine having a bottom wall, a handle, means pivotally sustaining said magazine and said handle, a leaf spring carried by said handle, fulcrum means traversing said handle, and a rockable cradle supported by said spring pivotally against said ful-
- 75 19. In combination, a staple carrying magazine having a bottom wall, a handle, means pivotally sustaining said magazine and said handle, a leaf spring carried by said handle, fulcrum means traversing said handle, and a rockable cradle supported by said spring pivotally against said ful-

crum means and having latch means for disconnectably interlocking with said magazine and accessible finger gripping means disposed forwardly of said latch means and extending laterally and outwardly of said wall to overhang said handle intermediate the latter and said magazine whereby said cradle may be bodily actuated for unlocking said latch means from said magazine.

10. The combination according to claim 8 wherein said cradle is a channeled member having spaced and notched sides pivotally sustained against said fulcrum means and said finger gripping means being disposed forwardly of said latch means and comprises spaced lips extending laterally and outwardly of said spaced sides of said magazine and between said handle and magazine, and said spring yieldingly urging said notched sides against said fulcrum means.

11. In combination, a staple carrying magazine having spaced sides, a handle, means pivotally sustaining said magazine and said handle, a leaf spring carried by said handle, fulcrum means carried by said handle, and a rockable cradle supported by said spring pivotally against said fulcrum means and having latch means for disconnectably interlocking with said magazine, and accessible finger gripping means projecting from said cradle and disposed forwardly of said latch means between said magazine and handle and extending laterally and outwardly of said magazine to overhang said handle for disconnecting said latch means from said magazine.

12. In combination, an upper handle comprising a head and downwardly sloping rear and flared portion, a lower handle comprising an upwardly sloping rear and flared portion swingably straddled by said downwardly sloping portion, a staple carrying arm interposed between said handles and having a rear part housed by said sloping portions, staple driving means slidably guided

by said arm, and fulcrum means pivotally sustaining said sloping portions and said rear part.

13. In combination, an upper hollow handle comprising a head and downwardly sloping rear and flared portion having spaced lips, a lower handle comprising an upwardly sloping rear and flared portion having spaced lips movably straddled by said spaced lips of said downwardly sloping flared portion, a staple carrying arm interposed between said handles and having a rear part movably straddled by said lips, staple driving means slidably guided by said arm, and fulcrum means pivotally sustaining said sloping portions and said rear part.

14. In combination, an upper handle comprising a head and downwardly sloping rear and flared portion having spaced lips, a lower handle comprising an upwardly sloping rear and flared portion having spaced lips straddled by said spaced lips of said downwardly sloping portion, a staple carrying arm interposed between said handles and having a rear part straddled and housed by said lips, staple driving means slidably guided by said arm, fulcrum means pivotally sustaining said sloping portions and said rear part, staple driving means carried by said arm, and a connection between said head and driving means.

15. In combination, an upper handle comprising a head and downwardly sloping rear and flared portion, a lower handle comprising an upwardly sloping rear and flared portion straddled by said downwardly sloping portion, a staple carrying arm interposed between said handles and having a rear part housed by said sloping portions, staple driving means slidably guided by said arm, and fulcrum means common to said handles and arm for pivotally sustaining said sloping portions and said rear part.

STEPHEN A. CROSBY.
